Primary Examiner — Cathron C Brooks*Assistant Examiner* — Andrew T Nemeth(74) *Attorney, Agent, or Firm* — Meunier Carlin & Curfman LLC(57) **CLAIM**

The ornamental design for a display screen with graphical user interface, as shown and described.

DESCRIPTION

FIG. 1 is a front view of a display screen with graphical user interface showing a first embodiment of my new design; and,

FIG. 2 is a front view of a display screen with graphical user interface showing a second embodiment of my new design. The outermost two broken lines illustrate the display screen. The remaining broken lines illustrate portions of the graphical user interface and display screen. None of the broken lines form part of the claimed design.

1 Claim, 2 Drawing Sheets(56)
